UNITED STATES PATENT OFFICE.

CHARLES M. LEE, OF NIAGARA FALLS, NEW YORK.

ABRASIVE-WHEEL TRIMMER.

1,115,693.

Specification of Letters Patent.

Patented Nov. 3, 1914.

Application filed January 12, 1914. Serial No. 811,737.

To all whom it may concern:

Be it known that I, CHARLES M. LEE, a citizen of the United States, residing at Niagara Falls, in the county of Niagara, State of New York, have invented certain new and useful Improvements in Abrasive-Wheel Trimmers; and I do hereby declare the following to be a full, clear, and exact description of the invention, such as will 10 enable others skilled in the art to which it appertains to make and use the same.

The present invention is directed to grind stone holders, and has for its object to so 15 construct a device of this character that different sizes of abrasive wheels may be held while being shaved or trimmed prior to the burning operation.

A further object of the invention is to 20 provide a device of this character which is durable, exceedingly simple in construction, cheap to manufacture, and one which will effectually hold a grind stone from becoming displaced during the rotation of the holder.

With these and other objects in view, this 25 invention resides in the novel features of construction, formation, combination and arrangement of parts to be hereinafter more fully described, claimed and illustrated in the accompanying drawing, in which:—

Figure 1 is a top plan view of the device, showing the same adapted to receive an abrasive wheel of capacity size. Fig. 2 is a similar view, showing the holder adapted to receive an abrasive wheel of less size. Fig. 3 is a bottom plan view of the device. Fig. 4 is a side elevation of the device. Fig. 5 is a sectional view on line 5—5 of Fig. 1. Fig. 6 is a similar view on line 6—6 of Fig. 2. Fig. 7 is a similar view on line 7—7 of Fig. 2. Fig. 8 is a sectional view through the device, showing the same adjusted for abrasive wheels comparatively thin.

Referring to the drawing, the numeral 1 designates a head, which may be rotated 45 rapidly in any suitable manner, said head being circular in shape and is provided with a plurality of sockets 2 for detachable engagement by the posts 3 carried by the wheel supporting disk 4, the upper surface of which is corrugated, as at 5, to cause the grind-stone when placed thereon to more readily rotate with the disk 4. To hold the disk 4 spaced from the head 1, the same is provided with feet 6, which engage the head 55 so that the material scraped from the wheels

may pass through the radially arranged slots 7 formed in the disk.

Secured to the periphery of the disk 4 is a band 8, the upper edge of which projects slightly beyond the upper surface thereof 60 so as to hold the sections 9 of the ring 10 in place so that when a wheel is resting upon the disk 4, said ring will prevent dislodgment of the grindstone during the rotation of the disk.

The height of the ring 10 is such that when a wheel is engaged upon the disk 4 one of the side faces thereof will be positioned slightly above said ring, and during the rotation of the disk a blade 11 is held in 70 contact with the face of the wheel, thus shaving or trimming the same.

When it is desired to trim wheels comparatively small, ring sections 12 are placed upon the disk 4 and a wheel engaged therebetween, said ring sections being held in place by pegs 13, which detachably engage the perforations 14 formed in the disk 4, said perforations being arranged in alignment so that rings of different diameters 80 may be interchangeably applied.

It is obvious that wheels of small diameters are of less thickness, and to facilitate the shaving of such wheels a supplemental disk 15 is employed, and is provided with a 85 plurality of posts 16 which are designed to detachably engage the perforations 17 formed in the disk 4, said disk being also provided with radially arranged slots 18 so that the scraped material may be readily 90 brushed from the disk. The disk 15 is of such thickness that when the same rests upon the disk 4 the upper surface of a wheel will be above the plane of the upper edges 95 of the ring sections 12.

Should a wheel be comparatively thin, sleeves 19 are engaged upon the posts 16 so that the upper surface of the grindstone will be properly positioned in respect to the ring sections 12, and as clearly shown in Fig. 8 100 of the drawing.

From the foregoing description it will be seen that a holder has been provided so constructed that wheels may be placed therein and properly shaved or scraped upon merely 105 applying a knife or blade to the rapidly rotating upper surfaces of the wheel.

What is claimed is:—

1. A holder of the class described, in combination with a rotary head, of a disk de- 110

tachably connected to the head, a ring detachably engaged on the disk, as and for the purpose set forth.

2. A holder, in combination with a rotary head, of a disk detachably connected to the head, a sectional ring removably engaged with the disk, and means carried by the disk for holding the same spaced from the head, as and for the purpose set forth.

10 3. A holder, in combination with a rotary head, of a disk detachably engaged with said head and adapted to rotate therewith, and a supplemental disk detachably connected to the first named disk, as and for the purpose set forth.

4. A holder, in combination with a rotary head, of a disk detachably connected thereto, spaced rings mounted upon said disk and arranged one within the other, and a supplemental disk detachably connected 20 to the first named disk and arranged in the innermost ring, and means for holding the supplemental disk in vertical adjusted positions in respect to the first named disk.

In testimony whereof, I affix my signature, in the presence of two witnesses.

CHARLES M. LEE.
